UNITED STATES PATENT OFFICE

100,555

DESIGN FOR A FINGER RING

Jack T. Goldman, New York, N. Y.

Application May 25, 1936, Serial No. 62,825

Term of patent 3½ years

To all whom it may concern:

Be it known that I, Jack T. Goldman, a citizen of the United States, residing at 48 West 48th Street, in the county, city, and State of New York, have invented a new, original, and ornamental Design for Finger Rings, of which the following is a specification, reference being had to the accompanying drawing, forming part thereof.

The figure is perspective view of a finger ring showing my new design.

I claim:

The ornamental design for a finger ring, as shown.

JACK T. GOLDMAN.
